UNITED STATES PATENT OFFICE

CHARLES ACHENBACH, OF MANITOWOC, WISCONSIN

HORN TRAINER

Application filed October 8, 1928, Serial No. 311,142, and in Canada May 4, 1928.

This invention relates to horn trainers.

This invention is an improvement over that disclosed in my Patent No. 1,681,565 of August 21, 1928, for horn trainers.

5 Objects of this invention are to provide a novel form of horn trainer which is so constructed that the horns may be manipulated, rotated, or bent at any desired portion of their length, so that the exact shape desired can be

10 easily secured.

Further objects are to provide a novel form of horn trainer which is so constructed that a plurality of different types of horn engaging members may be employed and any 15 one used with the horn training attachment by merely securing such horn engaging member to a clip or lever arm operated by the attachment.

Further objects are to provide a novel form 20 of horn training device which is of extremely simple construction, which may be readily produced, and which may be used in a variety of ways.

Further objects are to provide a horn engaging attachment which can be used to generally draw the horns towards each other or force them apart, which can be used to provide a sharp bend at any part of the horn desired to counteract defects, which may be used to twist or rotate the horn, and which although having the great flexibility in use, as discussed above, nevertheless is easy to regulate and is cheap to produce.

35 Further objects are to provide a horn engaging member in which its parts are reversible, in which spaced arms or apertured plates are provided for engaging a horn at spaced points, and in which means are provided for engaging the horn and preventing rotation of the member with respect to the horn.

Embodiments of the invention are shown in the accompanying drawings in which:

40 Figure 1 shows one form of the device as it appears when applied to the horns to draw them together;

Figure 2 is a view of the device showing it in a different position;

45 Figure 3 is a sectional view on the line 3—3 of Figure 2;

Figure 4 is a sectional view on the line 4—4 of Figure 3;

Figure 5 shows a further form of the device;

Figure 6 is a detail of one of the portions 55 illustrated in Figure 5;

Figure 7 shows a still further form of the device;

Figure 8 is a detail of the form shown in 60 Figure 7.

Referring to the drawings, it will be seen that the horns are indicated by the reference character H and that the horn engaging members 1 are provided with two parallel ears and with a base portion 2. The ears are apertured, as shown most clearly in Figure 3, with the aperture in one ear larger than the aperture in the other ear in order to properly receive the horns which are usually tapered. A 65 lever arm or clip 3 is removably carried by 70 each of the horn receiving members 1 and consists of a central portion provided with a multitude of apertures 4 at spaced intervals and having a pair of outwardly turned base portions 5 which bear against the inner side 75 of the connecting portion 2 of the horn engaging members. These outwardly turned feet 5 or base portions are secured removably by means of bolts 6 so that any desired type of horn engaging member may be used with 80 one of the lever arms or detachable arms.

In using the device, a turn buckle 7 has its outwardly projecting threaded stems 8 inwardly turned to provide end hooks 9. These end hooks engage in the apertures 4 when 85 the turn buckle is tightened, suitable lock nuts 10 being provided so as to lock the turn buckle in adjusted position.

It is apparent that the arms 3 may be attached to the horn engaging members so that 90 the arms point in either direction. These arms curve, as shown in Figure 1, and it is apparent that if a sharper bend in the horn is required than that produced in the construction shown in Figure 1, that it is a simple matter to reverse the position of the arms 3 so that they point upwardly (see Figure 95 4). Thereafter, when the turn buckle is hooked into the arms and tightened a sharper bend will be produced in the horns.

It is apparent that either a very gradual bend in the horns may be produced or else a sharp bend to correct defects in any portion of the horn.

5 It is also sometimes desirable to rotate the horn slightly. This is readily accomplished by projecting the arms 3 either forwardly or rearwardly, as required, and thereafter tightening the turn buckle. This tends to rotate 10 the arms in addition to drawing them towards each other. In order to prevent the horn engaging members 1 from slipping from the horns, particularly when this rotating action is taking place, these horn engaging 15 members are provided with notches 11 within which V-shaped clips or gripping members 12 are provided, such gripping members having sharpened edges. The gripping members are shown particularly in Figures 3 and 4, 20 and it will be seen that as the horn engaging member is positioned downwardly upon the horn that these gripping members firmly engage the horn and prevent relative rotary motion of the horn engaging members with 25 reference to the horns.

In the form shown in Figure 5, means are provided for forcing the horns apart. This is also readily accomplished by means primarily of the structure previously described 30 when associated with a separating bolt 13 provided with threaded upwardly projecting ears 14 carried thereby. These upwardly projecting arms 14 are provided with hook-like portions 15 which engage the holes 4 in the arms 3. Thus, when the bolt is turned the 35 horns may be pushed apart, as required. It is preferable to provide one or more apertures 15 in the screw 13 so that a pin may be slipped therein and the screw rotated with ease. Suitable locking nuts 16 are provided for locking 40 the parts in their adjusted position.

Referring to Figure 7, it will be seen that the previously described construction, particularly as shown in Figure 1, is employed.

45 The turn buckle 7 is turned until the slot is vertical. Under these conditions, it is a simple matter to pass the bolt 17 from an additional attachment upwardly through the turn buckle. This bolt 17 is rigidly carried 50 by the overlapping members 18 of a telescopic base portion. This base portion is provided with divergent downwardly extending looped portions 19 which engage beneath the base of the horns. Preferably, the marginal 55 edges of the overlapping portions 18 are folded to provide guides. Each of the members 18 is slotted, as indicated at 20, and receives the bottom of the bolt 17. After the required adjustment has been secured, the 60 bolt 17 is locked in place by means of the nuts 21 positioned on opposite sides of the members 18. Thereafter, the upper horn engaging members, previously described, are positioned with the bolt 17 passing through 65 the turn buckle 7. Preferably, a pair of

washers 22 are positioned on opposite sides of the turn buckle and are locked between a wing nut 23 and a lock nut 24. It is apparent that the horns may be drawn downwardly as much as required by gradually tightening 70 the wing nut and backing the lock nut 24 downwardly.

It will be seen that a very simple type of horn training device has been provided which may be cheaply constructed, which 75 may be adjusted to correct any one of a multitude of defects in the horns of animals, and which may be used in conjunction with a base portion to draw the horns downwardly towards the head, if required.

80 It will also be seen that the device is extremely simple and may be cheaply produced and easily applied.

85 Although the invention has been described in considerable detail, such description is intended as illustrative rather than limiting as the invention may be variously embodied and as the scope of such invention is to be determined as claimed.

90 I claim:

1. A horn engaging member including a base portion having laterally disposed spaced ears, said ears having apertures with the aperture in one ear larger than the aperture in the other ear, said base portion having a slot therethrough, an arm having a plurality of perforations therethrough extended through the slot with laterally disposed portions extending over the base and secured thereto.

100 2. A horn engaging member including a base portion having laterally disposed spaced ears, said ears having apertures with the aperture in one ear larger than the aperture in the other ear, said base portion having a slot therethrough, an arm having a plurality of perforations therethrough extended through the slot with laterally disposed portions extending over the base and secured thereto, said ears having V-shaped notches 105 and V-shaped clips fitted within said notches and their edges projecting into the apertures in the ears.

110 In testimony that I claim the foregoing I have hereunto set my hand at Manitowoc, in 115 the county of Manitowoc and State of Wisconsin.

CHARLES ACHENBACH.
